UNITED STATES PATENT OFFICE.

LAWRENCE CONNELL, JR., OF PORTLAND, OREGON.

ELECTROMAGNET.

945,018.

Specification of Letters Patent.

Patented Jan. 4, 1910.

Application filed July 2, 1906, Serial No. 324,305. Renewed May 20, 1909. Serial No. 497,326.

To all whom it may concern:

Be it known that I, LAWRENCE CONNELL, Jr., a citizen of the United States, residing at Portland, in the county of Multnomah 5 and State of Oregon, have invented certain new and useful Improvements in Electromagnets, of which the following is a specification.

This invention relates to improvements in 10 electromagnets and it has for its general object to provide a magnet by means of which an armature may be operated to vibrate in either of two directions by simply increasing or decreasing the current strength, without 15 out changing current direction and without depending upon springs or gravity to act in opposition to the magnetic force.

The invention is adapted for use in various 20 connections but finds a special application when employed in quadruplex or multiplex telegraphy. When thus employed, the salient object of the invention is to overcome or obviate false signals in the neutral relay incident to the working of the pole 25 changers on the polar side of the quadruplex, such signals being due to what are technically termed "moments of no magnetism" in the line. I accomplish this end by so constructing my improved relay that it 30 depends for its operation on no force other than the magnetizing forces developed in it. That is to say, I so construct the magnet 35 that it is unnecessary to employ a spring, gravity or other outside force to pull the armature back from the front stop, as has heretofore been common.

It is well understood that in quadruplex 40 telegraphy, the common side is subject to false signals and that the system is quite sensitive to unfavorable weather conditions, so that nothing but an extremely perfect adjustment of instruments and conditions on both common and polar sides will permit of its successful operation.

The chief and most frequent fault inherent 45 to the instruments of the common side is the false signals induced by moments of no magnetism. These moments of no magnetism are caused by the operation of the 50 pole changers, which in placing first one, and then the other, pole of the battery to the line inevitably produce intervals when either both poles are placed to line at once, or neither pole is to line. These moments al- 55 though exceedingly brief are nevertheless sufficient to cause false signals, and this is

particularly true in operating long lines, in which case the flow of current in the line does not reach its maximum and minimum strength instantly but the current assumes a 60 wave-like aspect which magnifies the moments of no magnetism.

It will be obvious that a relay so constructed that its armature is free from the action of external force, such as a spring or gravity and which responds only to variations in the strength of the magnetism induced therein, will be free from the fault of giving false signals, since its armature will remain passive during the moments of no magnetism. The underlying principle which I employ in constructing such a relay is the disproportionate magnetization of a mass of iron under inductive currents of varied strengths. To explain more specifically, it 7 is found that in magnetizing soft iron the increase or decrease of magnetism induced in the iron is not at all proportional to the increase or decrease of current used. If, commencing with an extremely small magnetizing force, this force is gradually increased, the corresponding increase in magnetic density would be as follows: At first the magnetic density would increase more slowly than the magnetizing force until the 85 latter had risen very considerably, but presently the magnetic density would increase faster than proportional to the increase of current and so continue through a considerable period of increase until the iron ap- 90 proached magnetic saturation, whereupon the increase of density would again fall off and be less than proportionate to the increase of current, and as the point of saturation was more and more nearly reached the 95 density would fall off correspondingly more and more rapidly until presently increase of current would be unaccompanied by any increase of magnetic density whatever. Applying this principle, if one magnet be 100 wound so comparatively low as to induce only 10,000 lines of force per square inch when magnetized by a twenty milli-ampere current (the small end of the battery commonly used in quadruplex telegraphy) and this current were then increased to sixty milli-amperes (representing the large end of the battery) the magnetic density would be found to have increased to 55,000 lines of force per square inch, or five and one-half times its former strength while the current strength had been increased only three times.

If another magnet be wound so high that when excited by the small end of the same battery it would induce 100,000 lines of force per square inch, it would be found that when the large end of the battery was applied, the magnetic density had increased to only about 120,000 lines of force per square inch, or an increase of about one-fifth while the current strength had been trebled. If, now, these two magnets were opposed to each other and excited by the same current it will be obvious that a soft iron armature placed between them would be vibrated toward the one or the other depending upon the increase or decrease of current strength, and this in fact is what occurs in a relay embodying a preferred form of my invention. It will be obvious that the details of construction of a magnet embodying this principle may be varied.

In the accompanying drawings I have illustrated (partly diagrammatically) a practical and what I deem a preferred embodiment of the invention as applied to a system of quadruplex telegraphy, of which one end or station only of the line is shown.

Referring to the diagram, A and A' designate a pair of low voltage generators having their negative and positive poles connected to line, respectively; B and B' a similar pair of high voltage generators likewise having their negative and positive poles connected to line, each of the series of generators having one pole connected to ground, as indicated at 1.

C and C' designate a pair of pole changers (these two instruments are usually made as a single instrument having one armature which controls two pairs of contacts), the armature, as 2, 3, of each of which operates between a pair of front and back contact screws, as indicated at 4 and 5, and 6 and 7. Contacts 4 and 5 are connected with generators A and A' through resistances D, and contacts 6 and 7 are similarly connected with generators B and B', respectively, through other resistances D. The coils of the pole changer magnets C, C' are inclined in series in a local circuit comprising a conductor 8, battery 9 and a key 10, so that the armatures 2 and 3 move together and in the same direction.

E designates as a whole the common transmitter, the armature 11 of which operates between the usual pair of contacts 12 and 13, which are respectively connected with the armatures 2 and 3 of the pole changers. The coil of transmitter E is included in a local circuit comprising a conductor 14, battery 15 and key 16.

The parts thus far described are all constructed and arranged in a usual manner.

F designates as a whole a relay embodying my invention and connected in the system shown in a manner corresponding to the

connections of the usual neutral relay, and accordingly hereinafter designated as the neutral relay. This relay comprises two main magnet spools 17 and 18, each differentially wound as indicated at 19, 19', and 20, 20', an armature 21 interposed and pivoted to vibrate between the poles of the two spools, and a pair of steady magnets 22 and 22' connected in series in a local circuit comprising the conductor 23 and battery 24. Armature 21 vibrates between contacts 25' and 25; the former of which is included in a local sounder circuit comprising a conductor 26, battery 27 and sounder G.

H designates as a whole the polarized relay comprising the usual opposed magnet spools 28 and 29, armature 30, and back and front contacts 31 and 32, respectively. Contact 31 is included in a local sounder circuit comprising a conductor 33 having one end connected with a contact 34 carried by the armature and its opposite end connected with the contact 31 and including a battery 34' and sounder I.

M designates the main line which is connected with armature 11 of the transmitter E, extends thence to and includes the windings 19' and 20' of the neutral relay (both wound in the same direction), thence extends to and includes the windings of the magnet 29 of the polarized relay and thence to the distant station.

N designates the artificial line which branches from the main line at a point between transmitter E and the neutral relay, includes the windings 19 and 20 of the neutral relay, extends thence to and includes the winding of the magnet 28 of the polarized relay and thence passes to ground at 35 through the usual rheostat 36; a condenser being arranged in shunt with the rheostat, as usual.

The differentially wound spool 17 of the neutral relay F is constructed with a core containing a relatively large amount of iron and is wound low as to both windings 19 and 19' so that a small current will have comparatively small magnetizing effect upon this spool while it is capable of taking a comparatively large current and becoming magnetized to a relatively high degree of density. Accordingly this spool is shown as made relatively long and the turns of the windings comparatively few in number, as indicated by the small diameter of the spool heads 17'. The spool 18, on the contrary, is so constructed as to have a relatively small amount of iron in its core, and the core is wound high as to both windings; this construction being indicated by the short core and the spool heads 18' of relatively large diameter. The steady magnets 22 and 22' of this relay simply serve the purpose of holding the armature steady against vibration during moments of no magnetism in the

main spools. To this end these magnets are of equal strength, symmetrically disposed with reference to the vibrating end of the armature so wound that they oppose each other and included in a closed circuit so that they are constantly energized.

The operation of the apparatus constructed and arranged as described should be entirely obvious from the foregoing description but may be briefly recapitulated as follows: Assuming a message is to be sent over the polarized side from the station shown, the pole changing key 10 is operated. When this key is open, armatures 2 and 3 engage contacts 4 and 6, respectively, and, armature 11 of transmitter E being at this time in engagement with contact 12, the negative generator of low voltage A is placed to line. When key 10 is closed, armatures 2 and 3 close, thus placing the positive generator of low voltage A' to line. Inasmuch as the circuit from the two high voltage generators is at this time open at contact 13, the latter generators are not concerned in the transmission over the polarized side. If a message is to be transmitted over the common side from the station shown, key 16 is operated. In the normal or open position of this key the negative low voltage generator A is placed to line through contact 4, armature 2, contact 12 and armature 11. When key 16 is closed the negative generator of high voltage B is placed to line through contact 6, armature 3, contact 13 and armature 11. In other words, current of 130 volts and current of 375 volts is placed alternately to line without changing the polarity. Neutral relay F being differentially wound as to both of its spools and half of the current going to ground at 35 over the "artificial line" and the other half over the main line, it follows that the neutral relay is unaffected by current sent from the home station whether it be increased or decreased, or reversed in polarity. For the same reason, viz: because the artificial line includes the windings 28 and 29 of the polarized relay H which are opposed to each other, the latter instrument is unaffected by signals of either strength or polarity sent from the home station. When the pole changing key at the distant stations is operated, the polarized relay H will respond in the usual and well understood manner. In transmitting a message over the common side, the low voltage generator is normally closed to line as hereinbefore described, and accordingly the low voltage current flowing through the coils of the neutral relay will magnetize the high wound coil to a greater degree than it does the low wound coil, with the result that the armature 21 will normally be closed with front contact 25 and the sounder G held in open position. When the distant transmitter key 16 is closed, and the generator of

higher voltage placed to line, the increase of current flowing through the two coils of the neutral relay will bring up the magnetic density of the low wound coil to such extent that it overpowers the opposing high wound magnet and the armature 21 will be drawn away from contact 25, thus closing the sounder circuit and causing the signal. The manner in which the current of higher voltage causes the low wound coil to overpower the high wound coil has been hereinbefore fully explained. In a word, the low voltage current which is normally flowing through the coils of the neutral relay energizes the high wound coil to a degree approaching saturation, and when the high voltage generator is placed to line, the high wound coil being already nearly saturated, increases in strength but little, while the opposed coil, owing to its larger size, increases in strength approximately proportionately with the increase of current, and thus overpowers the smaller coil.

At the moments of no magnetism during the operation of the pole changer key, the armature of the neutral relay obviously remains passive or without movement because there is no exterior force acting upon and tending to move it.

As hereinbefore stated, the inductively opposed windings, and the iron or fields magnetized thereby, may be variously arranged to secure the result of vibrating an armature or movable member under the inductive force generated in two windings opposed to each other in accordance with the principle of this invention. For instance, it will be obvious that polarization of the armature may be affected by including it in a field subject to the inductive action of opposed high and low windings, in accordance with this invention. Accordingly the appended claims are to be interpreted broadly except in so far as they are made specific in terms.

I claim as my invention:

1. In an electromagnet the combination of two magnet members, one having a relatively small core and high winding and the other a relatively larger core and low winding, an armature associated with said magnet members and arranged to be acted upon by the latter in opposition to each other, and a source of electric energy connected with and common to both magnet members, whereby they are simultaneously energized and act in opposition to each other and the magnetic strength of one or the other preponderates as the amplitude of the current varies.

2. In an electromagnet the combination with a movably mounted armature of two inductive windings arranged to act upon said armature inductively and in opposition to each other, one of said windings being made relatively high to magnetize its core to

- 4
- a degree approaching saturation under the action of a relatively small flow of current and the other of said windings being made relatively low to energize its core to a relatively low degree of magnetization under said relatively small flow of current and to overpower the opposed magnet under a relatively large flow of current, and a source of variable current connected with and common 10 to both of said windings.
3. In an electromagnet the combination of a high wound smaller magnet member and a low wound larger magnet member connected in series and inductively opposed 15 to each other, a member operatively associated with and acted upon by both said magnet members, and means for supplying variable current to said magnet members.
4. In an electromagnet, two opposed inductive windings, an armature member subject to the inductive action of each winding, a source of variable current and conductors connecting said windings in series with each other, one of said windings being wound to 20 move the armature against the opposed inductive force under a relatively small current flow and the other wound to move the armature against the opposed inductive force under a relatively larger current flow.
5. In an electromagnet, the combination of two magnet members, one having a relatively small core and two differentially disposed high windings and the other a relatively larger core and two differentially disposed low windings, an armature associated 30 with said magnet members and arranged to be acted upon by the latter in opposition to each other, and two conductors, respectively connecting the pair of high and low windings of the same direction in series with each other and themselves electrically connected at one side of the relay.
6. In an electromagnet, the combination of two magnet members, one having a relatively small core and two differentially disposed high windings and the other a relatively 40 small core and two differentially disposed low windings, an armature associated with said magnet members and arranged to be acted upon by the latter in opposition to each other, two conductors, respectively connecting the pair of high and low windings of the same direction in series with each other and themselves electrically connected at one side of the relay.
7. In an electromagnet, the combination of two magnet members, one having a relatively short core and two differentially disposed high windings thereon forming a coil of relatively large diameter, the other a relatively long core and two differentially disposed low windings thereon forming a coil of relatively small diameter, an armature interposed between the poles of said magnet members and pivoted to oscillate toward either magnet member, and two conductors 65 each of which connects the high winding of one magnet member with the similar direction low winding of the other magnet member in series, said two conductors being electrically connected with each other at one side of the relay.
8. A relay comprising two magnets connected in series, one wound high to approach magnetic saturation under moderate current excitation and the other wound low and arranged to inductively overpower the first under current of relatively large amplitude, and an armature-controlled contact device associated with said magnets and shiftable thereby in either of two positions, dependent 80 upon which of said magnets at the time predominates inductively.
